BRUSH ATTACHING DEVICE FOR SCRUBBING MACHINES

Filed Dec. 29, 1930

UNITED STATES PATENT OFFICE

HAROLD J. POND AND WILLIAM THIELEN, OF MINNEAPOLIS, MINNESOTA, ASSIGNEES
TO ADVANCE MACHINE COMPANY, INC., OF MINNEAPOLIS, MINNESOTA, A CORPORATION OF MINNESOTA

BRUSH ATTACHING DEVICE FOR SCRUBBING MACHINES

Application filed December 29, 1930. Serial No. 505,304.

Our invention relates to brush attaching devices for scrubbing machines and particularly to scrubbing machines having a driven shaft for driving a rotary brush and has for an object to provide a device whereby the brushes of a scrubbing machine may be rapidly and easily mounted in the machine.

Another object of the invention resides in providing an attaching device by means of which the brush may have universal movement with respect to the support therefor.

A still further object of the invention resides in providing a device in which the brush is yieldingly held in a position such that the axis thereof is in alignment with the axis of the brush shaft and may be moved out of such position to conform to irregularities in the surface upon which the brush is operating.

26 An object of the invention resides in providing a resilient keeper adapted to be detachably secured to the brush shaft for holding the brush in place upon said shaft.

25 A feature of the invention resides in constructing the shaft with a stop or shoulder against which the brush is disposed and in flexing said resilient keeper to urge the brush against said shoulder.

30 An object of the invention resides in detachably securing one end of said resilient keeper to the brush shaft.

Another object of the invention resides in constructing the brush shaft with a transverse laterally opening slot and in forming 35 the resilient member with a tongue for engagement within said slot.

A still further object of the invention resides in constructing the resilient keeper in the form of a coil spring and in bending the end of said coil spring to cause the same to extend diametrically with respect thereto, for engagement within the slot and said shaft.

40 An object of the invention resides in constructing said slot with the inner portion thereof a distance from said shoulder greater than the distance of the open portion thereof from said shoulder.

45 A still further object of the invention resides in constructing the coil spring of such

diameter that the finger of the user may be inserted between the stud and spring.

Another object of the invention resides in constructing the tongue so that the same projects outwardly beyond said slot on one side 55 thereof to permit of the insertion of the finger of the user between said stud and spring and in back of said tongue for disengaging said tongue from said slot.

Other objects of the invention reside in 60 the novel combination and arrangement of parts and in the details of construction hereinafter illustrated and/or described.

Fig. 1 is a perspective view of a scrubbing machine having an embodiment of our invention and applied thereto.

Fig. 2 is a bottom view of the structure shown in Fig. 1.

Fig. 3 is an elevational sectional view taken on line 3—3 of Fig. 1.

Fig. 4 is a fragmentary plan sectional view taken on line 4—4 of Fig. 3 and drawn to a larger scale.

Fig. 5 is a vertical sectional view of part of the structure shown in Fig. 3, drawn to a 75 larger scale and with the brush and brush shaft rotated through an angle of 90 degrees.

Fig. 6 is a perspective view of the spring keeper utilized with the invention.

Fig. 7 is a fragmentary detail view of a 80 stud illustrating another form of slot therein.

In the use of the ordinary scrubbing machine having detachable brushes universally mounted in the machine, considerable noise is occasioned where the brushes are loose upon the driving shafts, due to the free movement of the parts when the machine is operated. The instant invention overcomes this disadvantage by providing an attaching device through which the brush is yieldably mounted in the device in a manner to prevent clattering or rattling.

For the purpose of illustrating our invention, I have shown a scrubbing machine in Fig. 1, which is indicated in its entirety at 10. 95 This machine comprises a body member 11, which is provided with a handle 12 issuing outwardly therefrom and which is further provided with supporting wheels, 13 and 14. Upon the body 11 is mounted an electric 100

motor 15 which has attached to the armature shaft thereof, a spur pinion 16. This pinion is adapted to drive two spur gears 17 which are rigidly secured to shafts 18 and 19, journaled in bearings 20 carried by the body 10. The shafts 18 and 19 extend outwardly beyond these bearings to provide studs 21 upon which may be mounted two brushes, 22 and 23. The spur pinion 16 meshes with one or the other of the two gears 17, which in turn mesh with one another, causing the two shafts 18 and 19 to rotate in opposite directions. The brushes 22 and 23 are preferably constructed triangular in form, so that the same intermesh and completely cover the sweep of the machine. Both of the brushes 22 and 23 are detachably mounted upon the shafts 18 and 19. These brushes and the attaching devices therefor being identical in construction, only the brush 23 and the device associated therewith will be described in detail.

The brush 23 may be of any suitable construction. For the purpose of illustration, the brush has been shown as constructed with a wood or similar back 24, having bristles 25 mounted therein in the usual manner. The back 24 as previously stated, is triangular in form and is provided at the center thereof with a hole 26 which extends completely through the same and is of somewhat larger dimensions than the stud 21. A circular recess 27 in the underside of the back 24 of brush 23 communicates with the hole 26 and is concentric with respect thereto. To limit the inward movement of the brush 23 upon the stud 21, said stud is formed smaller in diameter than the shaft 19, to provide a shoulder 29 adjacent the end of the bearing 20. A casting 28 is secured to the stud 21 adjacent to the shoulder 29 and may be held in place upon said shaft by any suitable means. This casting is formed with a three cornered portion 30 at the lower end thereof terminating in a spherical shoulder 31. The triangular portion 30 of this casting is adapted to be received within a triangular hole 32, formed in a flanged plate 33, secured to the upper surface of back 24 of brush 23 through ordinary wood screws 34. This plate is centrally secured with respect to the hole 26 in brush 23, so that the triangular portion 30 of casting 28 may form a drive for rotating said brush.

In the application of the brush to the machine, the back 24 rests against the rounded shoulder 31 of casting 28. In the construction of the brush, both the hole 26 and the triangular opening 32 are considerably larger than the parts fitting within the same, so that the brush may have universal movement with respect to the shaft 19 to cause the brush to conform to the surface along which it travels. In this manner the brush is caused to fit flat upon the floor regardless of the length of the

bristles 25 and also independently of irregularities in the floor.

Our invention proper comprises a device for detachably securing the brush upon the stud 21, which device comprises a keeper shown in detail in Fig. 6 and indicated in its entirety at 35. This keeper consists of a compression coil spring having two or more convolutions 36, which spring is provided at one end thereof with a portion 37, bent from the end of one of the convolutions 36 to extend diametrically across the spring. This member serves as a tongue and is used for attaching the keeper to the stud 21. For this purpose, the stud 21 is provided with a transverse slot 38, opening laterally of the stud 21 as indicated at 39 and extending in an oblique manner, as best shown in Fig. 5, to cause the inner end thereof to be disposed at a distance from the shoulder 31, greater than the distance of the outer portion thereof from said shoulder, which portion is designated by the reference numeral 39. This construction forms a laterally extending finger 50 at the end of the shaft. The keeper 35 is disposed within the recess 27 and the free end 41 thereof is seated against the portion 40 of back 24 within said recess. The tongue 37 on said keeper is adapted to be inserted into the slot 38 and to be retained therein through finger 50.

The use of our invention is as follows: When it is desired to mount the brush in the machine, the machine is inverted and the brush slipped over the stud 21 with the casting 28 extending into the opening 32 of plate 33 and with the stud 21 extending through the opening 26. This is readily accomplished, since the parts fit loosely within said openings. The spring 36 is next placed within the recess 27 with the portion 41 thereof contacting with the portion 40 of the back 24 within said recess. Keeper 35 is next compressed by applying pressure to the tongue 37. At the same time, the tongue 37 is moved laterally until the same clears the stud 21. When the keeper 35 has been sufficiently compressed, the tongue 37 may be inserted into the slot 38 through the open end 39 thereof. Upon releasing the keeper, tongue 37 becomes lodged within the inner end of said slot and due to the oblique disposition of said slot, is firmly maintained within the same through finger 50. The machine is now ready for use and the brushes held in place upon the studs 21 through the keepers 35.

When it is desired to remove either of the brushes, it is merely necessary to insert the index and second fingers between the spring 35 of the desired brush and stud 21 and in back of the tongue 37. By exerting a lateral pressure upon the tongue, the same is readily withdrawn from engagement from the slot 38. When the tongue is free from said slot, the compression in the spring 35 forces the

same outwardly, which completely disengages said tongue from the stud 21. The brush and spring may now be independently or jointly removed from the device.

- 6 The slots 38 in the stud 21 may be constructed by milling the end of said stud in the manner shown, the milling cutter being positioned obliquely with respect to the axis of the shaft 19. The slot 38 may also be 10 constructed as shown in Fig. 7 by first drilling a round hole 42 in the end of the stud 21 and by then milling a slot 43 in said stud, communicating with said hole at one side thereof to leave a shoulder 44 therebetween.
- 15 In this case the milling cutter may be disposed at right angles to the shaft. The shoulder 44 in this form of the invention, serves the same purpose as the inclination in the slot 38 and prevents the tongue 37 from 20 being unintentionally disengaged therefrom.

The advantages of our invention are manifest. The device is extremely simple in construction and can be manufactured at a nominal cost. The device is quite easy to apply 25 and remove and does not require tools of any nature whatsoever for this purpose. When the device has been applied, the brush is yieldingly held in proper position and when so held, clattering or any noise ordinarily 30 produced in the operation of similar devices is prevented. The brushes may be used until the bristles are worn down to the back, if desired, and without procuring any undesired noise or other disadvantages.

35 Changes in the specific form of our invention as herein disclosed may be made within the scope of what is claimed, without departing from the spirit of our invention.

Having described our invention, what we 40 claim as new and desire to protect by its patent is:

1. In combination with a stud, a stop on said stud, a member on said stud movable toward and from said stop, a resilient keeper on said stud for urging said member against 45 said stop and means on said keeper to releasably engage said stud for holding the member detachably mounted upon said stud.

2. In combination with a stud, a stop on 50 said stud, a member on said stud movable toward and from said stop, a resilient keeper on said stud for urging said member against said stop, a tongue on said keeper, said stud having a laterally extending opening for the 55 reception of said tongue, said tongue being movable into and out of said opening.

3. In combination with a stud, a stop on 60 said stud, a member on said stud movable toward and from said stop, a resilient keeper on said stud for urging said member against said stop, a tongue on said keeper, said stud having a laterally opening slot adapted to receive 65 said tongue, said tongue being laterally movable into and out of said slot.

4. In combination with a shaft, a member

axially slidable on said shaft, a stop on said shaft for engagement with said member for limiting axial movement of said member, a compression coil spring encircling said shaft and urging said member against said stop, 70 said shaft having a socket opening laterally thereof and a tongue on said spring movable laterally into engagement with said socket for holding said spring in engagement with said member. 75

5. In combination with a stud, a stop on said stud, a member on said stud movable toward and from said stop, a coil spring encircling said stud for urging said member against said stop, the end of said spring being 80 bent to form a diametrically extending tongue, said stud having a transverse laterally opening slot for the reception of said tongue.

6. In combination with a stud, a stop on said stud, a member on said stud movable toward and from said stop, a coil spring encircling said stud for urging said member against said stop, a slot formed in said stud transversely thereof and opening in a lateral direction, said slot being oblique with respect to the axis of said stud and a diametral tongue on said spring for lateral insertion into said slot. 85

7. In combination with a stud, a stop on 90 said stud, a member on said stud movable toward and from said stop, a coil spring encircling said stud for urging said member against said stop, said stud having a slot formed therein extending transversely thereof and opening in a lateral direction, said slot having a portion at the end thereof, a greater distance from said stop than the open end of said slot and a tongue on said spring for engagement with said slot. 100

8. In combination with a stud, a stop on said stud, a member on said stud movable toward and from said stop, a resilient keeper on said stud for urging said member against 105 said stop, said stud having a transversely disposed slot opening laterally thereof, the inner end of said slot being a greater distance from said stop than the open end of said slot and means on said keeper for engagement within said slot. 115

9. In combination with a stud, a stop on said stud, a member on said stud movable toward and from said stop, a resilient keeper on said stud for urging said member against said stop, said stud having a transverse slot 120 extending partially through the same, and beyond the axis thereof, and a diametrically extending tongue on said keeper for engagement with said slot, said tongue being adapted to intersect the axis of said stud when in 125 normal position.

10. In combination with a stud, a stop on said stud, a member on said stud movable toward and from said stop, a compression coil spring encircling said stud and adapted 130

to urge said member against said stop, said stud having a laterally extending opening, a tongue on said spring movable into and out of said opening, said spring being of a size such that the difference between the internal diameter of said spring and the lateral dimension of said stud in the direction of movement of said tongue is greater than the length of the movement of said tongue.

10 11. In combination with a stud, a stop on said stud, a member on said stud movable toward and from said stop, a coil spring encircling said stud and spaced therefrom, said stud having a laterally opening transverse

15 slot, a tongue extending diametrically from said spring for lateral movement into and out of engagement with said slot, said tongue projecting outwardly beyond said stud on both sides thereof to provide finger pieces 20 for engagement with the fingers of the user in the movement of the tongue into and out of said slot.

12. In combination with the brush shaft of a scrubbing machine, having a free end, 25 means on said shaft forming a shoulder, a brush positioned upon the free end of said shaft and inwardly of the extreme end thereof, and resilient means on the free end of said shaft and removably secured to said shaft for holding said brush detachably mounted thereon and for urging it against said shoulder.

13. In combination with a stud, a stop on 30 said stud, a member on said stud movable toward and from said stop, a resilient keeper on said stud for urging said member against said stop, a finger on said stud, and means on said keeper for releasably engaging said finger to hold the member detachably mounted upon said stud.

40 14. In combination with a brush shaft of a scrubbing machine having a shoulder thereon and a free end extending outwardly therefrom, a brush having a body fitting loosely over the free end of said shaft and adapted 45 to rock on said shoulder and a resilient member attached to the free end of said shaft and engaging said brush body to urge the same against said shoulder, said member flexing laterally to accommodate the rocking movement of said brush.

15. In combination with a brush shaft of a scrubbing machine having a shoulder thereon and a free end extending outwardly therefrom and provided with spring engaging 55 means, a brush having a body fitting loosely over the free end of said shaft and adapted to engage said shoulder and having a recess in the outer portion thereof to form a seat and a compression coil spring seated in said seat and against said spring engaging means to urge the brush body against the shoulder.

60 16. In combination with a brush shaft of a scrubbing machine having a shoulder thereon and a free end extending outwardly therefrom and provided with spring engaging

means, a brush having a body fitting over said shaft and engaging said shoulder, a driving member on said shaft having a salient angle, a member attached to said brush body having a surface extending away from the same and forming a reentrant angle for cooperation with said driving member and a spring operating between said spring engaging means and brush body to urge the brush against said shoulder.

70 In testimony whereof we have affixed our signatures.
